UNITED STATES PATENT OFFICE.

DAVID BERTULEIT, OF PORTLAND, OREGON.

ELECTRICALLY-HEATED PUFF-IRON.

1,304,146.

Specification of Letters Patent. Patented May 20, 1919.

Application filed June 22, 1918. Serial No. 241,398.

To all whom it may concern:

Be it known that I, DAVID BERTULEIT, a citizen of the United States, residing at Portland, in the county of Multnomah and State of Oregon, have invented certain new and useful Improvements in Electrically-Heated Puff-Irons, of which the following is a specification, reference being had to the accompanying drawings.

10 This invention relates to devices for ironing garments, and particularly to what are known as puff irons used in tailoring, laundry and dyeing establishments for pressing ruffles, silk waists, etc.

15 The object of this invention is to provide an improved puff iron of a very convenient form which is electrically heated, thereby rendering the iron much easier to manipulate with much less danger of burning the 20 fabric than where the iron is heated by steam or gas.

A further object is to provide an iron of this character which has a head approximately ovoidal, the head being mounted 25 upon a standard and the head being formed of two sections detachable from each other and having disposed between the sections a heating element.

Other objects will appear in the course of 30 the following description.

My invention is illustrated in the accompanying drawings, wherein:—

Figure 1 is a vertical sectional view of a puff iron constructed in accordance with my 35 invention;

Fig. 2 is a top plan view of the head with the top section removed.

Referring to these figures, 10 designates the head of the puff iron which is approximately ovoidal in form and may be of any suitable material, preferably metal, and which is formed in two sections connected by screws 11 passing through the lower section into the upper section, these screws 45 having screw-threaded engagement with the upper section. The head has an interiorly screw-threaded bore 12 through the lower section for engagement by a screw-threaded

standard 13 preferably tubular in turn engaged with a base 13^a.

Disposed between the upper and lower sections of the head 10, is the electrically energized heating element 14, which, as illustrated in the drawing, is held between the opposing faces of two longitudinally extending strips 15 of insulating and refractory material, these strips being laid face to face and being clamped between the two sections of the head 10, the screws 11 passing through these strips as shown. Conductors 16 extend up through the standard 13 and are electrically connected to the heating element 14, and these conductors are combined in a cord which passes out of the standard 13 and connects to the usual plug 17.

It will be seen that exteriorly the head 10 is smooth and is of such shape as to make it particularly convenient for all kinds of ironing of the character stated by reason of the fact that it is egg shaped so that surfaces of various degrees of curvature are presented to the work. The heat may be readily controlled by any of the usual electrical controlling means such as a rheostat and thus there is no danger of scorching the fabric and inasmuch as the current need not be turned on at all until the iron has been inserted within the garment or disposed in proper position, there is no danger of the hands of the operator being burned.

What I claim is:—

1. A puff iron, comprising a head formed in two complementary sections, strips of refractory and insulating material applied to the opposing faces of said sections and extending longitudinally thereof and in abutting relation to each other and clamped between said sections, an electrical heating element interposed between said strips and held thereby, a hollow standard extending through one of said sections, a base upon which said standard is mounted, and conducting wires passing through said standard and connected to said heating element.

2. In an electrically heated puff iron, a head composed of two complementary sec-

tions, longitudinal strips of insulating and refractory material interposed between the adjacent faces of said sections and in contact therewith and with each other, a heating element interposed and clamped between said strips, means for connecting said sections together with the strips and heating element clamped between them, and means

for conducting an electrical current into said head to said heating element.

In testimony whereof I hereunto affix my signature in the presence of two witnesses.

DAVID BERTULEIT.
